US00D926781S

(12) **United States Design Patent** (10) **Patent No.:** **US D926,781 S**
(45) **Date of Patent:** **** Aug. 3, 2021**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Patrick Lee Coffman**, San Francisco, CA (US); **Stephen O. Lemay**, Palo Alto, CA (US); **Christopher Daryl Soli**, Mountain View, CA (US)

(73) Assignee: **Apple Inc.**, Cupertino, CA (US)

(**) Term: **15 Years**

(21) Appl. No.: **29/692,707**

(22) Filed: **May 28, 2019**

(51) LOC (13) Cl. **14-04**

(52) U.S. Cl.

USPC **D14/485**

(58) **Field of Classification Search**

USPC ..... D14/485—495
CPC G06F 3/048; G06F 3/0481; G06F 2203/04803; G06F 2203/04805

CLAIM

The ornamental design for a display screen or portion thereof with graphical user interface, as shown and described.

DESCRIPTION

The sole FIGURE is a front view of a display screen or portion thereof with graphical user interface showing the claimed design.

The peripheral dashed broken lines illustrate a display screen or portion thereof, and form no part of the claimed design. The interior broken lines illustrate portions of the graphical user interface which form no part of the claimed design.
